(57) **CLAIM**

I claim the ornamental design for the corrugated roof panel for a storage shed, as shown and described.

DESCRIPTION

FIG. 1 is a front perspective view of a corrugated roof panel for a storage shed;
 FIG. 2 is a rear elevation view of the corrugated roof panel for a storage shed;
 FIG. 3 is a left side elevational view of the corrugated roof panel for a storage shed, the right side of which is symmetrical;
 FIG. 4 is a top plan view of the corrugated roof panel for a storage shed; and,
 FIG. 5 is a bottom plan view of the corrugated roof panel for a storage shed.
